(57) **CLAIM**

The ornamental design for a water purifier, as shown and described.

DESCRIPTION

FIG. 1 is a front, right perspective view of a water purifier showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a top plan view thereof, illustrating the swivel nozzle rotated at a predetermined angle. The dashed lines indicate the unrotated position.

This claimed water purifier is provided in a shape where trapezoidal corner portions are processed to be round and thereby the overall design shape provides a unified creative esthetic sense. Two buttons (cold water/warm water buttons) and a swivel nozzle having a "T" shape are provided in an upper portion of the water purifier.

The portions shown in broken lines are for illustrative purposes and form no part of the claimed design.
